TOY SEA HORSE

Mary Alice Massey, 226 W. Jackson Blvd.,
Webster Groves, Mo.

Filed Jan. 4, 1961, Ser. No. 63,438

Term of patent 14 years

(Cl. D34—2)

FIG. 1 is a side view of a toy sea horse in accordance with my new design. The opposite and unseen side of the article is substantially the mirror image of FIG. 1.

FIG. 2 is a perspective view of the toy sea horse of FIG. 1.

I claim:

The ornamental design for a toy sea horse, substantially as shown and described.
